[57] **CLAIM**

The ornamental design for a step tube table, substantially as shown and described.

DESCRIPTION

FIG. 1 is a front perspective view of a step tube table embodying my new design; and
FIG. 2, is a top plan view thereof.

The rear perspective view of the step tube table of my design is identical with the front perspective view and the bottom plan view thereof is identical with the top plan view.

Fig. 1.

Fig. 2.
